UNITED STATES PATENT OFFICE

JOHN D. MACLACHLAN, OF KANSAS CITY, MISSOURI, ASSIGNOR TO MAC-AD-CO., OF KANSAS CITY, MISSOURI, A CORPORATION OF MISSOURI

ADVERTISING CARD DISPLAY DEVICE

Application filed July 9, 1930. Serial No. 466,676.

This invention relates to automatic display devices of that class involving the use of cards pivotally mounted on a revolving carrier so that the cards on the carrier shall be successively displayed, and the display repeated in the same order as long as the device is in operation. It also relates to devices of the character indicated in which the cards are so relatively arranged with respect to the direction of travel, that the rear face of each card shall cooperate with the front face of the following card in the display of a single advertisement, the two cards at the display period occupying substantially the same vertical plane in relatively inverted positions. It has also been proposed with devices of the character described to employ rotary carriers having peripheral pivotal openings for the respective cards, so that each of the latter in the interim between one display and the next, shall extend at an angle to a radial plane bisecting the outer edge of the card and the axis of the carrier during upward travel within the casing, and thus permit of the use of a cabinet of smaller size from top to bottom and from front to back than would be necessary if the cards in such travel occupied a radial position with respect to the axis of the carrier.

In all the devices of the character mentioned which have come under my observation, the pivotal point of each card remains at a fixed distance from the axis of rotation of the carrier, and one of my objects is to make provision for an automatic shifting of such pivotal points and thereby reduce to a substantial extent the distance which each card projects from the axis of the carrier in travelling upward in the interim between the display of their rear sides and the later display of their front sides to the observer, thus permitting the use of a shallower cabinet.

Another object is to produce a display device operable by a relatively small and weak motor, and this object is attained by providing for a closer approach of the pivotal points or trunnions of the cards to the axis of the carrier in the upward travel mentioned, of the cards.

Another of my objects therefore is to employ slots in the carrier for the pivotal points

or trunnions of the cards, so that such points shall, in the upward travel of the card from a point below the axis of the carrier to about the horizontal plane of such axis, move inward and thus reduce the leverage and thereby the power required to carry the cards upwardly, the use of such slots furthermore permitting of a reduction in the height of the cabinet as well as in its rearward depth.

Another object is to provide flat pivots or trunnions for the cards which will enable each of the latter to bodily drop downward and then move upward as it swings from its upper display position to its lower display position, and in such action cause its hinged edge to engage the adjacent corresponding edge of the following card and slightly raise the same so that what may be termed the inner or butt edges of two cards in display position shall abut and by thus closing the joint between them, present the two displayed cards to the eye as a single card.

Another object is to provide each card with a holding frame and its hinge or inner edge with rounded clips to facilitate the swinging of each card from its upper to its lower position against the preceding card, and to provide springs for holding the cards pressed yieldingly edgewise against the said clips to insure close butt engagements of displaying cards, and to facilitate the removal and replacement of a card when necessary.

One of the objects is to provide a device which is peculiarly adapted for use as an advertisement in street cars, motor busses and the like, and which therefore must be capable of withstanding the ordinary jolting and shaking incident to travel of such cars and busses, and another objective is to provide a construction which makes provision for the removal and the replacement of any one or more of the cards when the motor to operate the same is inactive, and to accomplish this I have provided a gearing or drive connection which automatically yields to permit the carrier to be rotated by hand without disturbing the gearing connection with the motor.

With these objects in view and others as hereinafter appear, the invention consists in

certain novel and useful features of construction and combinations of parts as herein-after described and claimed; and in order that it may be fully understood, reference is 5 to be had to the accompanying drawings, in which:

Figure 1 is a side elevation of an automatic display device embodying the invention, with the near side of the cabinet omitted.

10 Figure 2 is a fragmentary front view elevation of the device as viewed from the front.

Figure 3 is an enlarged fragmentary elevational view indicating how each card as it swings from upright to inverted position applies a slight lifting action on the following card so that the butt or hinge edges of the cards shall stand in abutting relation when functioning to conjunctively display the advertising matter on their forwardly facing 20 sides.

Figure 4 is a fragmentary detailed perspective view of two cards in display position.

25 Figure 5 is a broken view showing the inner edge of one of the cards and a part of the holder exposed by omitting a portion of the card.

Figure 6 is a broken elevational view of one 30 of the cards disposed in inverted position, and also showing the holder therefor partly in section.

Figure 7 is an end view of the construction disclosed by Figure 6.

35 Figure 8 is a fragmentary vertical section showing the connection between the driving mechanism and the carrier.

Referring now to the drawings in detail, 40 1 indicates a cabinet open at the front side except for a cross piece or head 2 and a bottom reflector 3, the reflector having the additional function of substantially hiding depending cards hereinafter identified, behind the foremost one from the view of a person stationed in front of the cabinet. An illuminating means 4 is preferably provided within the reflector so that the latter shall diffuse light upon the exposed faces of the two front superposed cards for conjunctive display of a single advertisement. If desired there may 45 be an equivalent illuminating means (not shown) at the top of the cabinet.

Arranged on a horizontal shaft 5 within 50 the cabinet and near the respective side walls thereof, is a rotary carrier consisting of a pair of disks 6, and said shaft is journaled at one end in any suitable manner in or to the adjacent side wall and at the other end secured to the respective disk, the latter being secured on the hub 7 of a gear wheel 8 journaled on a stub shaft 9 screw-bolted at 9^a against and projecting inwardly from the respective side wall, a cap screw 10 engaging the inner end of said stub shaft and through the interposition of a washer 11 retaining 55 said gear wheel on the stub shaft. Verti-

cally below the carrier is a second stub shaft and journaled thereon is a small gear 12 meshing with the large gear 8, and rigid and in concentric relation with the small gear, and interposed between the large gear and the adjacent side wall of the cabinet, is another large gear 13 which meshes with an idler gear 14 journaled on the rear end of a lever 15 pivoted at its front end to the last mentioned side wall, said lever having a guide slot 16 engaging a fixed screw 17 mounted in the side wall, and to hold the lever flatly against the latter, a washer 18 is interposed between the head of said fixed screw and the lever.

70 The idler gear meshes with a small pinion 19 rigid with a large worm wheel 20 suitably journaled in the cabinet, the arrangement being such that rotation of the worm wheel in the direction indicated by the adjacent arrow, Figure 1, exerts through the engagement of the pinion with the idler gear, a lifting force on the latter and the lever, to hold said idler gear in intermeshed relationship to the large gear 13, and as a precautionary measure it is desirable to employ a spring 21 exerting force in the same direction, that is to raise the gear end of the lever.

75 By the arrangement described it will be apparent that as long as the worm wheel is in operation, it is exerting a lifting force on the lever through the connection mentioned, and hence holds the idler gear in intergeared relation with the large gear 13. The worm wheel is driven by the motor 22, the shaft of the latter having a worm 23 meshing with the worm wheel. Should the motor be inactive and it be desired at such time to turn the carrier in the direction indicated by the adjacent arrow, Figure 1, for the purpose of bringing a card or cards through the front opening of the cabinet to permit of ready removal or replacement, it is apparent that the carrier can be rotated in the direction of 80 said last mentioned arrow, as the instant this action starts the gear wheel 13 exerts force on the idler gear and the latter utilizing the pinion 19 as a resistance point, moves downward until the idler is disengaged from the said gear wheel, it being obvious that in this 85 operation a slight clicking sound will be noticeable as the teeth of the said gear wheel successively ride over the teeth of the idler which cannot rotate because of its interlocked engagement with the said pinion 19, and the instant the turning of the carrier is stopped, the spring will re-elevate the idler against or into gear with the said gear wheel. Should the spring merely raise the idler against the teeth of the gear wheel 13, the operative intergeared relationship between the two will 90 instantly be reestablished when the motor is again started up, as the latter in applying force to the pinion on the idler gear to rotate the same will incidentally lift it back

into intergeared relation with the said gear wheel 13.

Referring again to the carrier, it will be noted that the disks are provided near their peripheries with circular series of slots 24, the series of slots being arranged in concentric relation with the axis of the carrier. The slots are preferably curved and may extend radially of the carrier. It is preferable however, that they extend at a slight angle to a radial direction, as it is believed that a certain shifting movement of the pivotal points or trunnions hereinafter mentioned, of the display cards, takes place more smoothly in the slots formed and arranged as shown than if straight and/or disposed exactly radial with respect to the carrier, it being understood of course that the principle and mode of operation will be substantially the same with either arrangement.

Each card is composed of two similar members 25 and 26 of the same form and size and fitted flatly together, and fitting between the inner edges of each pair of said members is a thin metal axle plate 27, terminating in aligned end trunnions 28 of oblong rectangular cross section, and each axle plate 27 has a plurality of U-shaped clips 29 fitting over and secured to its inner edge and disposed angularly thereof, the legs of each clip being spaced apart so that the plate and the two card members fitting flatly against it, shall lie snugly between the legs of the clip, and in order that two cards when standing respectively in upright and inverted positions in substantially the same vertical plane, shall abut together edgewise and thus present to the observer a substantially continuous card, the clips are embedded slightly in the edges of the respective axle plates 27 and likewise in the adjacent edges of the cards engaging such plates.

The clips 29 are disposed at identical points along the length of the cards, so that those on an upwardly-projecting card shall come into direct bearing contact with those on an underlying inverted card, it being noticed however that when a card is inverted from an upright to a hanging or pendant position, the angle of the clips thereon will intersect the angles of the clips on the overlying or upright card. Hence, as a card swings from its upright to its pendant position, the engaged clips of the two cards will take up the wear that would otherwise be imposed on the edges of the cards. In other words, the clips not only serve to retain the inner or hinge edges of the card members flatly against the respective axle plates 27, but eliminate friction in a large measure in the turning action of each card from an upright to a pendant or inverted position.

The two card members while movable together, are designed to bear unrelated advertising matter as their faces are never concur-

rently exposed to view, and either member is designed for replacement without disturbing the other, but for holding each pair of card members, I have provided a U-shaped frame of thin metal of channel form, each frame 70 consisting of an outer or cross piece 30 paralleling the axle plate and receiving the outer edges of the two members 25 and 26, and end arms 31 receiving the ends of said members, and projecting inwardly from 75 and forming extensions of the arms 31, are bars 32 engaging the respective trunnions 28 of the axle plates 27. The bars 32 hold the flattened trunnions against turning movement relative to the frame, and arranged 80 within the channel of the cross piece 30 are two or more springs 33 which engage the outer edges of the card members and hold them pressed edgewise against the clips 29, the springs being repressible by the card members when the latter are forced by hand power, to cause their inner edges to pass from between the legs of the clips and then be spread apart preliminarily to the removal of the members. To place the members within 90 a holding frame, they are slid within the channeled cross piece 30 against the resistance of springs 33 until their inner edges clear the ends of the respective clips of the axle plate, and then said edges are caused to approach 95 and bear flatly against opposite sides of cross piece 27. When thus disposed the outward pressure on the card members is relaxed and the springs 33 permitted to force them inwardly between the legs of the clips and the 100 axle plate 27 until arrested by the bridge portions of the clips.

Cards and holders constructed and arranged as described make provision for the ready replacement of the member or members of a card when accessible by projection through the front opening of the cabinet, and as stated the cards can be brought to the accessible point mentioned when the carrier is in operation under power of the motor, or the carrier can be rotated by hand for such purpose, when the motor is not in operation. This changing of the cards in display devices for use in street cars and the like, will ordinarily be made when the cars 115 or busses are not in service or are stationary and hence when the motor is not in operation, and for this reason a construction permitting of the turning of the carrier by hand is very desirable.

In Figure 2 appears the approximate relative positions of all of the cards when the two foremost cards are in abutting relationship at their inner edges, one projecting upwardly and the other downwardly, and it will 125 be noted that the leverage resistance of a large proportion of the cards when travelling upwardly within the cabinet, is reduced by reason of the fact that their trunnions are disposed at or near the inner ends of the respec-

tive slots of the disks, it being noted that at a certain angle the inner end of one upwardly moving card engages the adjacent face or side of the next card in advance and applies pressure thereon toward the back of the cabinet to cause the outer end of said card to swing rearwardly and upwardly, and as a result of this action the trunnions of the card thus subjected to pressure, move in the respective slots nearer the axis of rotation of the carrier. This action is repeated by the last-mentioned card on the next card in advance and so on until the horizontal plane of the axis of the carrier is reached, at which time the card disposed with its trunnions in approximately the horizontal plane of the axis of the carrier has its trunnions at the inner ends of the respective slots. From the plane mentioned the position of the trunnions of the cards is reversed, that is to say they gradually move outward in the slots until they successively reach a point vertically above the axis of the carrier. The card at the top of the axis of the carrier will extend approximately horizontal under the pressure of the underlying card and the inner end of the said horizontal card will be applying upward pressure on the preceding card, and then the trunnions of the cards as they travel around the carrier will again move gradually inward. Two or three of the foremost cards occupying an upright or upstanding position will lean against the front or head piece of the cabinet and against each other, the foremost card however will underlie the head piece and bear against the stop pin 34 depending from the head piece, and about the time it attains this position the card ahead of it which under rotation of the carrier was withdrawn from behind the stop pin, swings by gravitational force to an inverted or pendant position. In this action, as it passes a horizontal position, its inner edge first drops slightly and then rises due to the use of the flat trunnions. The dropping action of the swinging card permits the foremost upright card to move downward slightly and the following upward movement of the swinging card, causes its hinge or inner edge to press upwardly and forwardly against the lower or hinge edge of the upright card so that the latter shall be slightly lifted and its hinge edge moved to the front or outer end of the respective slots and therefore stand in substantially the same vertical plane as the hinge or upper edge of the swinging card as the movement of the latter ceases upon attaining a pendant and inverted position. The two cards thus form in effect a single card facing an observer and maintain such relation until the slowly moving carrier lowers the upright card enough for its outer edge to clear the pin 34 and in turn swing downward and expose its rear side to view. The action described is repeated to display different advertisements until

the carrier has made a complete revolution. It will be understood from the foregoing that the front face of the upright card and the rear face of the inverted underlying card bear related matter constituting a single advertisement and the rear face of the upright card engaging the pin, will, when inverted, present advertising matter related to that which appears on the second or following upright card when the same is in operative or display position. 70 75

I claim:

1. In a device of the character described, a rotary carrier having a pair of spaced disks provided with opposite series of peripheral openings and a series of cards between the disks and having fixed pivots or trunnions at their inner corners loosely engaging opposite openings of the disks, the pivots being substantially oblong-rectangular in cross-section and disposed with their greater width paralleling the faces of the respective cards and their lesser width at right angles to the faces of the cards, the flat form and loose fit of the pivots in the disk openings permitting the inner or hinged edges of the cards, by the time the latter have attained a horizontal position in swinging from an upwardly-projecting toward a pendent position, to move downward, and then causing such edges of the respective cards to move upward as the movement of the cards proceeds, by the continued turning action of the pivots on the lower edges of said openings, until the wider faces of the pivots stand in an approximately vertical position. 80 85 90

2. In a device of the character described, a rotary carrier having spaced disks provided with opposite circular series of peripheral slots, the slots of each disk bearing an inwardly converging relation, and a series of cards fitting between the disks and provided at their inner corners with flattened pivots engaging opposite slots of the disks, the pivots being narrower at their wider sides than the width of the engaged slots, and capable of bodily shifting movement in the latter transversely and longitudinally as well as rotatably, the wider sides of the pivots being disposed parallel with the faces of the respective cards and the narrower sides at right angles to the faces of said cards, the pivots being set back from the inner edges of the cards to permit such edges when the respective cards are projecting upward approximately vertically, to occupy a horizontal plane below that of the respective slots. 100 105 110 115

3. In a device of the character described, a rotary carrier, a series of cards around the carrier, the cards having pin-and-slot connections at their inner ends with the carrier, permitting gravitational swinging movement of the cards relative to the carrier and also providing for automatic shifting movement of the pivoted ends of the cards nearer to or 120 125 130

further from the axis of the carrier while the latter is in motion.

4. In a device of the character described, a carrier comprising a shaft and a pair of spaced disks thereon each provided with a circular series of substantially radial slots, a series of cards corresponding in number to one series of said slots and disposed at their inner ends between the disks and provided at such ends with laterally projecting trunnion pins, the pins projecting in one direction engaging the respective slots of the adjacent disk and the pins projecting in the other direction engaging the corresponding slots of the other disk; the said trunnion pins being of less diameter in both directions than the width of the respective slots and of smaller diameter at right angles to the faces of the respective cards than in the direction paralleling such faces, to cause the respective cards to gravitate from an upright position to a pendant position and in describing such movement to move downward and then upward at their pivoted ends relative to the axis of the carrier.

5. In a device of the character described, a cabinet open at its front side, a horizontally arranged carrier journaled in the cabinet adjacent the open side thereof, a series of cards arranged around and pivotally mounted on the carrier adjacent the periphery thereof and adapted as they successively attain an upwardly projecting position at the open side of the cabinet, to expose their front sides to view and then under the rotation of the carrier, swing to a vertically pendant position to expose their opposite sides to view, a motor geared to the carrier for imparting continuous slow movement to the latter to cause the cards to successively function as stated, said gearing including a driving pinion, a train of gearing permanently intergeared with the carrier, and an idler gear permanently geared to said pinion and held by the latter in yielding engagement with said train of gearing and adapted under rotation of the pinion by the motor to impart rotation to the train of gearing in the direction to effect the proper movement of the carrier and the cards for the display of the latter, and adapted when the motor is inactive and the carrier is turned by hand in the proper direction, to yield under the pressure of the train of gearing to permit the latter to turn, the idler gear fulcruming on the said pinion in such yielding movement without becoming disengaged therefrom.

6. In a device of the character described, a motor, a worm shaft driven thereby, a large worm wheel engaging the worm, a gear pinion rotatable with the worm wheel, a rotary card carrier, a train of gearing connected to the carrier to operate the same, a lever, and an idler gear journaled on the lever and permanently meshing with said pinion and nor-

mally held by the latter in intergeared relation with the train of gearing, and adapted when the motor is at rest and the carrier is turned, to yield to the pressure of the train of gearing to permit the latter to turn without transmitting rotation to said pinion, and adapted when the pinion is properly turned by the motor, to resume its intergeared relation with the train of gearing to cause the same and the carrier to operate.

7. In a device of the character described, a motor, a worm shaft driven thereby, a large worm wheel engaging the worm, a gear pinion rotatable with the worm wheel, a rotary card carrier, a train of gearing connected to the carrier to operate the same, a lever, an idler gear journaled on the lever and permanently meshing with said pinion and normally held by the latter in intergeared relation with the train of gearing, and adapted when the motor is at rest and the carrier is turned, to yield to the pressure of the train of gearing to permit the latter to turn without transmitting rotation to said pinion, and adapted when the pinion is properly turned by the motor, to resume its intergeared relation with the train of gearing to cause the same and the carrier to operate, and a spring applying force on the lever tending to hold the idler gear in intergeared relation to the train of gearing.

8. In a device of the character described, a hinge plate, a pair of cards fitting at their inner ends against the opposite sides of said hinge plate, a U-shaped channeled card holder frame receiving the outer ends and side edges of the pair of cards, bars secured to the side portions of said frame and non-rotatably engaging the hinge plate, yielding means carried by said frame and applying inward pressure against the outer edges of the cards, and means for holding the inner ends of the cards flatly against the hinge plate and for limiting inward movement of the cards under the pressure of said yielding means.

9. In a device of the character described, a hinge plate, a pair of cards fitting at their inner ends against the opposite sides of said hinge plate, a U-shaped channeled card holder frame receiving the outer ends and side edges of the pair of cards, bars secured to the side portions of said frame and non-rotatably engaging the hinge plate, yielding means carried by said frame and applying inward pressure against the outer edges of the cards, and substantially U-shaped clips extending diagonally through the hinge plate at its inner edge, the arms of said clips extending outwardly and spaced from the respective sides of said plate to hold the inner ends of the respective cards interposed between the hinge plate and said arms.

10. In a device of the character described, a display element comprising a holder frame

of substantially U-shape, a hinge plate in the same plane as but spaced from the inner ends of the arms of the holder frame and paralleling the bridge portion of said frame, bars constituting extensions of the arms of said frame and non-rotatably connected to said plate, substantially U-shaped clips at the inner edge of and secured to said plate, and a card slidably carried by said U-shaped frame and interposed at its inner end between the hinge plate and said clips.

11. In a device of the character described, a display element comprising a holder frame of substantially U-shape, a hinge plate in the same plane as but spaced from the inner ends of the arms of the holder frame and paralleling the bridge portion of said frame, bars constituting extensions of the arms of said frame and non-rotatably connected to said plate, substantially U-shaped clips at the inner edge of and secured to said plate, a card slidably carried by said U-shaped frame and interposed at its inner end between the hinge plate and said clips, and springs secured to the said frame and applying yielding outward pressure against the outer edge of the card; the springs being adapted to yield enough when pressure is applied to force the card outward, to permit the inner edge of the latter to clear the outer ends of the clips for facilitating the insertion or removal of the card relative to the holding frame.

12. The combination of a carrier rotatable around a horizontal axis, a series of flat axle plates between and journaled at their ends in the carrier, a series of pairs of cards, each pair fitting flatly together and against the respective axle plate, the pivotal points of the plates being outward of the inner edges of the cards, similar diagonally-disposed clips secured to the respective axle plates at equal distances from their ends and fitting around the inner edges of the respective cards and holding them flatly against the respective axle plates, the clips of adjacent pairs of cards, when one pair is extending upwardly and the other pair downwardly in approximately the same vertical plane, engaging and extending in intersecting planes oblique to the axis of the axle plates.

In testimony whereof I affix my signature.
JOHN D. MACLACHLAN.
